UNITED STATES PATENT OFFICE.

GUSTAVE O. MATTER, OF PORTLAND, OREGON, ASSIGNOR TO JOHN W. MACKAY, OF PORTLAND, OREGON.

POISON-BOTTLE INDICATOR.

1,086,724.

Specification of Letters Patent.

Patented Feb. 10, 1914.

Application filed May 3, 1911. Serial No. 624,880.

To all whom it may concern:

Be it known that I, GUSTAVE O. MATTER, a citizen of the United States, and residing at Portland, in the county of Multnomah and State of Oregon, have invented certain new and useful Improvements in Poison-Bottle Indicators, of which the following is a specification.

This invention relates to improvements in poison bottle indicators and has for its object to provide an indicator which can be cheaply made and easily attached to the neck of a bottle in such manner as to prevent the use of the contents of the bottle without properly operating the indicator. I attain this object by means of the improvements illustrated in the accompanying drawings, in which,

Figure 1 is a front elevation of the indicator, showing it attached to the neck of a bottle. Fig. 2 is a side elevation. Fig. 3 shows a top view of the indicator detached from the bottle.

Like numerals of reference indicate similar parts throughout the several views.

In the drawings the indicator is shown to consist of an inverted U-shaped spring wire 1 having its ends 4 spirally formed and attached by soldering, or, other suitable means, to a spring band 3 which is flat and circular in shape and adapted to engage the neck of the bottle 2. The ends of the band 3 may be joined if desired or the band may be cemented to the neck of the bottle 2.

In order to remove the cork 5 after the indicator has been attached to the neck of the bottle 2 as shown in Fig. 1, the inverted U-shaped part 1 may be deflected to the position shown dotted at 1^a or as at 1^b, and

when released will spring back into its proper position again.

It will now be seen that the contents of the bottle cannot be used by mistake, the indicator covering the cork automatically at all times except when purposely deflected.

It is understood that slight changes may be made in the specific structure shown without departing from the spirit of the invention.

What is claimed is:

1. A poison-bottle indicator comprising a circular band adapted to engage the neck of a bottle, and a U-shaped wire having ends spirally formed and attached to said circular band.

2. A poison-bottle indicator comprising an inverted U-shaped spring wire, and a circularly bent strip of flat metal attached to and between the ends of said inverted U-shaped wire in such manner as to hold a portion of said U-shaped wire over and in line with the axis of said circularly bent strip of flat metal.

3. A poison-bottle indicator comprising an inverted U-shaped spring wire having its ends spirally formed, and means for attaching said ends to a bottle.

4. A poison-bottle indicator comprising a circular band, and a U-shaped spring wire having its ends spirally formed and attached to said circular band.

In testimony whereof I affix my signature, in presence of two witnesses:

GUSTAVE O. MATTER.

Witnesses:

A. J. MATTER,
AGNES BUTTS.
